US00D561085S

(12) **United States Design Patent** (10) **Patent No.:** **US D561,085 S**
Wai (45) **Date of Patent:** **** Feb. 5, 2008**

(54) **HELICOPTER PROPELLER**(75) Inventor: **Chi Pok Billy Wai**, Quarry Bay (HK)(73) Assignee: **Silverlit Toys Manufactory, Ltd.**,
Hong Kong (HK)(**) Term: **14 Years**(21) Appl. No.: **29/282,295**(22) Filed: **Jul. 16, 2007****Related U.S. Application Data**

(63) Continuation of application No. 11/627,919, filed on Jan. 26, 2007, which is a continuation-in-part of application No. 11/465,781, filed on Aug. 18, 2006, which is a continuation-in-part of application No. 11/462,177, filed on Aug. 3, 2006, application No. 29/282,295, which is a continuation-in-part of application No. 29/275,322, filed on Dec. 20, 2006, now Pat. No. Des. 546,269, and a continuation-in-part of application No. 29/275,323, filed on Dec. 20, 2006, now Pat. No. Des. 544,825, and a continuation-in-part of application No. 29/275,324, filed on Dec. 20, 2006, now Pat. No. Des. 545,755, and a continuation-in-part of application No. 29/277,652, filed on Mar. 5, 2007, now Pat. No. Des. 552,531, and a continuation-in-part of application No. 29/280,187, filed on May 18, 2007, now Pat. No. Des. 554,040.

(51) **LOC (8) Cl.** **12-07**(52) **U.S. Cl.** **D12/345; D21/442**
